ELECTRICAL RECEPTACLE

Peter M. Schmidt, Decatur, Ga., assignor to National Service Industries, Inc., Atlanta, Ga.

Filed Feb. 12, 1973, Ser. No. 331,990

Term of patent 14 years

Int. Cl. D13—03

U.S. Cl. D26—1 B

FIG. 1 -

FIG. 6 -

FIG. 3 -

FIG. 2 -

FIG. 4 -

FIG. 5 -

FIG. 7 -

FIG. 13 -

FIG. 12 -

FIG. 11 -

FIG. 9 -

FIG. 10 -

FIG. 14 -

FIG. 1 is a perspective view of an electrical receptacle embodying my new design;

FIG. 2 is a front elevational view of the electrical receptacle shown in FIG. 1;

FIG. 3 is a left side elevational view of the electrical receptacle shown in FIG. 1;

FIG. 4 is a right side elevational view of the electrical receptacle shown in FIG. 1;

FIG. 5 is a back side elevational view of the electrical receptacle shown in FIG. 1;

FIG. 6 is a top plan view of the electrical receptacle shown in FIG. 1;

FIG. 7 is a bottom plan view of the electrical receptacle shown in FIG. 1;

FIG. 8 is a perspective view of a modified embodiment of an electrical receptacle embodying my new design;

FIG. 9 is a front side elevational view of the electrical receptacle shown in FIG. 8;

FIG. 10 is a right side elevational view of the electrical receptacle shown in FIG. 8;

FIG. 11 is a left side elevational view of the electrical receptacle shown in FIG. 8;

FIG. 12 is a back side elevational view of the electrical receptacle shown in FIG. 8;

FIG. 13 is a top plan view of the electrical receptacle shown in FIG. 8; and

FIG. 14 is a bottom plan view of the electrical receptacle shown in FIG. 8.

I claim:

The ornamental design for an electrical receptacle, as shown and described.
